HARRY C. GAMMETER, OF CLEVELAND, OHIO, ASSIGNOR TO THE AMERICAN MULTIGRAPH COMPANY, OF CLEVELAND, OHIO, A CORPORATION OF OHIO.

PROCESS OF MAKING PRINTING-SLUGS.

1,122,724.

Specification of Letters Patent.

Patented Dec. 29, 1914.

Application filed August 8, 1913. Serial No. 733,722.

To all whom it may concern:

Be it known that I, HARRY C. GAMMETER, a citizen of the United States, residing at Cleveland, in the county of Cuyahoga and 5 State of Ohio, have invented a certain new and useful Improvement in Processes of Making Printing-Slugs, of which the following is a full, clear, and exact description, reference being had to the accompanying 10 drawings.

The ultimate object of this invention is to provide a very cheap and efficient line slug adapted to be easily mounted in a grooved or slotted holder for printing. The holder 15 may be a portion of a printing machine. It may, for example, be an individual plate which, with a few of my slugs, may constitute an address plate. An effective form of a slug for use in such slotted or grooved 20 plate is one wherein the slug has lateral flanges adapted to rest on the top surface of the plate and receive the printing pressure, and has a shank or rib extending through the slot of the plate, and has means adapted 25 to engage the under side of the plate to prevent the slug falling out. Such slug is, therefore, in effect, grooved on its opposite sides and is of short height compared to ordinary linotype slugs.

30 It is difficult to make side grooves accurately after a slug is cast. The operation is also comparatively expensive. My process provides means whereby the slug may be first cast in a standard Mergenthaler machine, with a modified mold and ejector, and 35 may thereafter be cheaply formed into a suitable slug for an address plate.

The present application relates to the 40 process; the mechanism adaptable to the Mergenthaler machine for casting the initial slug is claimed in my divisional application No. 801,170, filed November 15, 1913; the finished slug is claimed in my divisional application No. 801,171, filed November 15, 45 1913.

Broadly considered, the process consists of casting the slug in a T-shape with up and down ribs on its sides and thereafter removing the bottom portion of the slug and the 50 top portion of the ribs to leave lugs extending from the sides of the shortened shank. I prefer to remove the bottom portion of the slug by shearing it off, and, at the same time, to flatten or compress the upper portion of the ribs sufficiently to leave the de-

sired projecting lugs. I then have my slug, comprising a shank, side flanges adjacent to the top and a series of side lugs adjacent to the bottom. The operation or operations subsequent to casting may be cheaply and 60 quickly performed; the slugs may be made, in the first place, in a linotype machine, and I have arranged the parts so that a very slight change is necessary in the standard commercial linotype machine. The construction enabling such adaptation and the shearing and compressing device constitute 65 my apparatus.

The invention is hereinafter more fully explained in connection with the accompanying drawings and the essential characteristics are summarized in the claims.

In the drawings, Figure 1 is a radial section of a Mergenthaler mold wheel showing my special mold in conjunction with a Mergenthaler melting pot and matrix; Fig. 2 is a similar view, showing the mold in position between an ejector and a pair of trimming knives; Fig. 3 is an isometric perspective of the slug cast in the mold shown in 75 Figs. 1 and 2; Fig. 4 is a cross section of the upper portion of the slug and the tool which severs and forms such portion, the remainder of the original slug being indicated by broken lines; Fig. 5 is an isometric perspective view of the finished slug; and Fig. 6 is a cross section of an address plate carrying 80 several of my slugs.

Referring to Figs. 1 and 2, 10 indicates the regular mold wheel of a Mergenthaler 90 machine. 11 is a special mold which I attach to this wheel. A indicates the slug cast by this mold, this slug appearing in Fig. 3, and also in Figs. 1 and 2 and illustrating the form of the mold. That is to say, the 95 mold has a long slot for the shank or body portion *a* of the slug, a pair of rabbets at the outer end of the slot for the head portions *a*¹, and grooves extending in a direction from the bottom toward the head for 100 the ribs *a*².

In Fig. 1, 12 indicates the melting pot and 13 the matrix, whereby the slug of the form shown in Fig. 3 and having the characters *a*⁴ along its top edge is cast. After the casting, the turning of the wheel 10 brings the slug between an ejector 16 and suitable trimming knives 17. To enable the standard Mergenthaler equipment to be used with 105 my mold, I form the ejector in a peculiar 110

manner; that is to say, its rear portion 18 has the thickness of a standard ejector and slides on the standard guide 19, while the front portion is reduced to the size of the shank of my slug and slides between a guide bar 20 and a suitable shim 21 between the blade and slide 19. By this construction I am able to use the slide 19 exactly as it is in the machine without altering anything except the end of the ejector, the block which guides it, and the mold. As will be seen, the operation of the ejector shoves the cast slug toward the right, in Fig. 2, between the trimming knives 17 which trim off any fin formed where the matrix abuts the mold.

When the slug has been cast and ejected, it is in the form shown in Fig. 3. I then submit this slug to the action of a pair of shearing and compressing members shown at 25 in Fig. 4. These two members have knife edges 26 adapted to shear through the ribs and shank of the slug to give it a substantially flat bottom, and they have portions 27 which engage the upper portions of the ribs a^2 and mash or flatten these ribs down almost to the plane of the shank a . The flattening is preferably not quite to this flange, so that there is no danger of disturbing the plane of the shank between these ribs. This is illustrated (in exaggerated form) by the slight remainders of these ribs shown at a^3 in Fig. 5. The portions 27 may be continuous ribs or spaced lugs somewhat wider than the ribs of the slug.

When the members 25 have come together, as shown in Fig. 4, they have sheared off the lower portion a^c of the slug and have left projecting lugs a^s on the sides of the shank. This completes the operation, producing a slug of the character shown in Fig. 5, which is readily adapted for insertion in a slotted address plate, as shown at B in Fig. 6. The space between the tops of the lugs and the under face of the side flanges constitute in effect side grooves. The address plate is slightly thinner than the up-and-down dimension of this groove.

The printing pressure may be taken by the shoulders or side flanges of the slugs through the plate to its support, or the slug bottom may rest on a suitable support. By carrying the pressure by the side flanges, however, I can avail myself of the accuracy of casting, and, as the plate may be made of accurate thickness, I can thus produce an address plate having the accurate "height-to-paper" desired. To prevent the formation of fillets at the junction of the head and shank, which might interfere with the accuracy of the effective height, I make the mold so that small grooves a^7 are cast in the under face of the head at the junction. This groove also provides space for the upper portion of the mashed rib.

It will be seen that my process is very simple and easily operated; that it produces very cheaply a slug which, in effect, is grooved on its opposite sides and has an accurate supporting head; that it may do this by the aid of a standard Mergenthaler machine very slightly modified and a combined shearing and pressing device of simple construction.

Having thus described my invention, what I claim is:

1. The process of making slugs consisting of forming the slugs with a shank and an overhanging head and up and down ribs on the side of the shank and thereafter removing an upper portion of the ribs while leaving a lower portion to provide in effect a longitudinal groove.

2. The process of making line slugs consisting of forming the slugs with ribs on the side and thereafter removing an upper portion of the ribs and the lower portion of the slug leaving an intermediate portion of the ribs, to provide a slug of short height having lugs on its side.

3. The process of making line slugs consisting of forming the slugs with a flanged head and up-and-down ribs on the side and thereafter removing an upper portion of the ribs below the flange and the lower portion of the slug, some distance below the removed portion of the ribs, to provide a slug of short height having a flange and lugs on its side.

4. The process of making line slugs consisting of forming the slug in a T-shape with ribs on its opposite sides and thereafter removing an upper portion of the ribs below the T-head, while leaving a lower portion separated from the head by the removed portion.

5. The process of making line slugs consisting of forming the slug in a T-shape with ribs on its opposite sides and thereafter removing an upper portion of the ribs below the T-head, while leaving a lower portion separated from the head by the removed portion, and removing a still lower portion of the ribs and of the shank of the T.

6. The process of making line slugs consisting of casting the slugs with a T-head and with up-and-down ribs on the sides thereof and thereafter removing an upper portion of the ribs to provide in effect a longitudinal groove.

7. The process of making line slugs consisting of casting the slugs with a shank and a head and up-and-down ribs on its opposite sides and thereafter removing the lower portion of the shank and the upper portion of the ribs, some distance above the plane of removal of the shank, the intermediate portion of the ribs being left intact.

8. The process of making line slugs con-

- 5 consisting of casting the slug in a T-shape with ribs on its opposite sides and thereafter removing an upper portion of the ribs below the T-head while leaving a lower portion intact.
9. The process of making line slugs consisting of casting the slugs in a T-shape with ribs on its opposite sides and thereafter removing an upper portion of the ribs below the T-head, and removing the lower portion of the ribs and shank, the intermediate portion of the ribs being left intact.
10. The process of making line slugs consisting of forming the slugs with up and down ribs on its opposite sides and thereafter removing the lower portion of the slug and mashing the upper portion of the ribs, while leaving the intermediate portion of the ribs intact.
- 15 11. The process of making line slugs consisting of forming the slug in a T-shape with ribs on its sides and thereafter removing the lower portion of the slug and mashing down the upper portion of the rib beneath the T-head and above the portion of the slug which is removed, while leaving the intermediate portion of the ribs intact.
- 20 12. The process of making slugs consisting of casting the slug in a T-shape with ribs on its opposite sides, and thereafter removing the lower portion of the slug and mashing down the upper portion of the ribs immediately beneath the T-head and some distance above the portion of the slug which is removed to leave portions of the ribs on outstanding lugs spaced from the head.
- 25 13. The process of making line slugs, consisting of casting the slug in a T-shape with separated ribs on its opposite sides, and thereafter removing the lower portion of the slug and removing a portion of the rib beneath the T-head and some distance above the severing plane at the bottom to leave intermediate lugs.
- 30 14. The process of making line slugs, consisting of casting a slug in a T-shape with a head and a shank and up-and-down ribs on the sides of the shank terminating at the head, and thereafter removing the lower portion of the slug and removing the upper portion of the ribs adjacent to the under side of the T-head and some distance above the plane of severing the lower portion whereby the intermediate parts of the ribs remain as lugs.
- 35 15. The process of making line slugs consisting of forming the slug in a T-shape with ribs on its opposite sides, and thereafter shearing off the lower portion of the slug and removing portions of the ribs some distance above the plane of shearing while leaving the ribs intact immediately above such plane.
- 40 16. The process of making line slugs consisting of forming the slug with a shank and T-head and with ribs on the opposite sides, and thereafter removing the lower portion of the slug and mashing down the upper portion of the ribs, while leaving portions of the ribs immediately below the mashed down part.
- 45 17. The process of making line slugs consisting of casting the slug in a T-shape with ribs on its opposite sides, and thereafter shearing off the lower portion of the slug and mashing portions of the ribs some distance above the plane of shearing, while leaving intact those portions of the ribs which are between the mashed portions and the plane of shearing.
- 50 18. The process of making line slugs consisting of forming the slug in a T-shape with ribs on its sides, and thereafter simultaneously shearing off the base of the slug and mashing the upper portion of the rib while leaving a lower portion thereof.
- 55 19. The process of making line slugs consisting of casting the slug in a T-shape with up-and-down ribs on its opposite sides, and thereafter simultaneously shearing off the base of the slug and mashing the upper portion only of the ribs, the mashed portion of the ribs extending slightly beyond the plane of the sides of the shank.
- 60 20. The process of making line slugs consisting of forming a T-shaped slug with ribs on its side, and simultaneously removing the lower portion of the entire slug and the upper portion only of the rib down to a plane which is a slight distance outside of the side planes of the shank.
- 65 21. The process of making line slugs consisting of casting the slug with a shank, a T-head and side ribs extending continuously in an up-and-down direction to the under face of the head, and thereafter removing the lower portion of the shank and ribs and only the upper portion of the ribs adjacent to the under face of the head.
- 70 22. In a process of making line slugs consisting of originally forming a slug with a shank and a T-head and ribs on opposite sides of the shank which extend a less distance than the overhang of the head, and thereafter removing the upper portions of the ribs below the T-head for a distance sufficient to cause the remaining portions of the ribs to present separated lugs.
- 75 23. The process of making line slugs consisting of casting the slug in a T-shape with up-and-down ribs on its opposite sides, which ribs do not extend the full width of the T-head, and thereafter removing approximately to the plane of the sides the upper portion of the ribs, while leaving lower portions projecting from such plane.
- 80 24. The process of making line slugs consisting in originally forming the slug with an overhanging head and up and down ribs,

and thereafter mutilating the upper portion of the ribs and removing the lower portion while leaving intact the intermediate portion.

5. 25. The process of making line slugs consisting in originally forming the slug with an overhanging head and up and down ribs, and thereafter mutilating the ribs at their upper portion immediately below the under 10 side of the head while leaving lower portions of the ribs as projecting lugs.

26. The process of making slugs consisting of casting the slug with a T-head and a shank, and thereafter treating the shank to 15 produce projections on opposite sides spaced from the head.

27. The process of making short height line slugs consisting of casting the slug with a T-head and a shank, and thereafter treating the shank to produce projections on opposite sides spaced from the head, and removing the shank below the projections, whereby there is produced a short-height 20 slug adapted to receive the printing pressure 25 on an original cast surface and provided with means for preventing its falling out of a holder therefor.

28. The process of making short height line slugs consisting of casting the slug with a T-head and a shank of considerable 30 height, and thereafter by pressure on opposite sides of the shank distorting its cast shape to make projections spaced from the head and removing the unused portion of the shank immediately below said projections. 35

29. The process of making slugs consisting of casting the slug with an overhanging T-head and thereafter distorting portions of the slug below the T-head and removing the bottom portion of the slug. 40

30. The process of making line slugs consisting of casting the slug with an overhanging T-head and without longitudinal 45 grooves, and thereafter by pressure changing the form of the sides to provide in effect longitudinal grooves.

In testimony whereof, I hereunto affix my signature in the presence of two witnesses.

HARRY C. GAMMETER.
